UNITED STATES PATENT OFFICE

106,225

DESIGN FOR A DENTAL UNIT

Louis H. Weinstein and Michael S. Weinstein,
Brooklyn, N. Y., assignors to Dental Equipment,
Inc., New York, N. Y.

Application December 24, 1936, Serial No. 66,734

Term of patent 14 years

To all whom it may concern:

Be it known that we, Louis H. Weinstein and Michael S. Weinstein, both citizens of the United States, both residing at Brooklyn, N. Y., in the county of Kings and State of New York, have invented a new, original, and ornamental Design for a Dental Unit, of which the following is a specification, reference being had to the accompanying drawing, forming a part thereof.

We claim:

The ornamental design for a dental unit, as shown.

LOUIS H. WEINSTEIN.
MICHAEL S. WEINSTEIN.
